KEY HOLDER

Isidor Newman, New York, N. Y.

Application November 24, 1936, Serial No. 112,599

14 Claims. (Cl. 70—456)

This invention relates to key holders.

An object of this invention is to provide in a key holder of the character described, loops which may be readily removed with a key thereon from 5 the supporting pivots individually, the construction being such that removal of one loop will not affect other loops on the key holder.

A further object of this invention is to provide in a key holder of the character described, a 10 key supporting loop mounted on the pivotal support and which is removable from the pivotal support and from which the key may be removed without removing the loop, the construction being such as to prevent accidental removal or loss 15 of either the keys or the loops.

Yet another object of this invention is to provide a strong, rugged and neat key holder of the character described, which shall be relatively inexpensive to manufacture, simple to manipulate, 20 and, withal, practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

30 In the accompanying drawing, in which is shown one of the various possible illustrative embodiments of this invention,

Fig. 1 is a front elevational view of a key holder with the flexible cover partly opened;

35 Fig. 2 is a perspective partial view of the key holder showing the position of the loop just prior to removal thereof from the pivotal support;

Fig. 3 is a view similar to Fig. 2, but illustrating the method of removing the loop;

Fig. 4 is a perspective view of a loop removed from the key holder with a key thereon;

Fig. 5 is a perspective view of a key retaining loop in open position permitting a key to be inserted or removed therefrom;

Fig. 6 is a top plan view of a blank from which my improved key retaining loop is made;

Fig. 7 is a partial perspective view of the key holder disclosing the position of the loop when 50 the key is to be removed from the loop without removing the loop from its pivotal support; and

Fig. 8 is a perspective view of a key retaining loop embodying a modified form of the invention.

Referring now in detail to the drawing, 55 designates a key holder embodying the invention,

comprising a flexible cover 11 of any suitable construction, and here shown for the purpose of illustration, as comprising a central portion 12 and flap portions 13 and 14 foldable over the central portion and adapted to be attached together in overlapping position, by complementary snap fasteners 15. Riveted or otherwise attached to the inner surface of the central portion 12 of the cover, and adjacent one end thereof, is a rigid, metal backing or supporting plate 16. 10 The same is provided with a plurality of aligned, spaced, projecting, rolled-over tab portions 17, supporting a fixed through pin 18. Pivotally supported on said through pin are a plurality of similar loop supports 20. 15

Each loop support comprises a cap-like member 21 having apertured ears 22 located in the spaces or notches 17a between the rolled-over portions 17 and receiving through the apertures, the elongated pin 18. Each cap 21 has a central 20 annular opening 24 and seated within the cap is a disc 25 having an outwardly pressed strap portion 26 extending through said annular opening. Each member 25 rotates about the axis of its cap 21 and about an axis perpendicular to the 25 axis of pin 18.

On each strap portion 26 is an improved key retaining loop 30. Each loop 30 is made of a resilient elongated flat strip of metal 31, shown in Fig. 6, and having similar end edges 32 adapted to be cut with the same die. The end edges are cut to provide similar, symmetrically disposed tabs 33 at the ends of each complementary rectangular strip 31 which are adapted to sidelap when the strip is bent on suitable tools to form 35 the loop 30. One tab is at one side edge of the strip and the other tab is at the other side edge of said strip. The tabs are complementary and the end edges forming the tabs come into contact when the loop is formed from the blank. Each 40 loop 30 is preferably of hour glass shape and is a continuous member, having a small loop portion 35 at one end and a large loop portion 36 at the other. Between the loop portions 35, 36 is a constricted portion 37, providing a space, however, through which a key or strap portion may be pushed. The complementary tab portions 33 are at the smaller loop portion 35 and disposed side by side and not in overlapping or underlapping relation, as clearly disclosed in Fig. 6 of 50 the drawing, thus saving in metal, simplifying manufacture and facilitating separation of the split ends of the loop.

Each loop engages a strap portion 26 and may be readily removed from the strap by separating 55

the edge-lapping tab portions 33, as shown most clearly in Fig. 5 of the drawing. When the tab portions 33 are separated to open the split end of the loop, the strap portion may pass between 5 the tabs. Upon releasing pressure from the loop the portions 33 move back into engaging or edge contacting position.

The key may also be removed from the loop without taking the loop off its pivotal support. 10 Such removal of the key may be accomplished by first maneuvering the loop to bring the strap into the larger loop portion 36, as disclosed in Fig. 7 of the drawing. The key may then be removed by again spreading the tab portions 33 15 of the smaller loop portion.

It will now be understood that the loops may be removed individually, and that removal of one loop does not affect removal of the others. Furthermore, as shown on the drawing, the loop 30 20 is continuous and of equal width all around.

It will be noted that the end edge of each tab 33 is perpendicular to the longitudinal axis of the strip 31. The end edges of the tabs contact parallel shoulders formed at the opposite ends of 25 the strip. With such construction the loop may be opened up to separate the split ends for insertion or removal of the key or for insertion or removal of a strap portion. However, the shoulders engaging the ends of the tabs act as stops 30 to limit movement of the split ends toward each other. The longitudinal contacting edges of said tabs are preferably located on the longitudinal axis of the strip 31, whereby said tabs are of equal width.

35 In Fig. 8 there is shown a key retaining loop 30a embodying a modified form of the invention. The loop 30a is likewise split at the upper end of the smaller loop portion 35 thereof above the constricted portion 37a thereof. The adjacent ends 40 and 41 of the smaller loop portion 35e, however, at the top overlap and are offset, one upwardly and one downwardly, to form shoulders 40a and 41a. The shoulder 40a at the inner end of the offset portion 40 serves as a stop for the 45 outer edge of the offset portion 41, whereas the shoulders 41a at the inner end of the offset portion 41 serve as a stop for the outer edge of the offset portion 40. The lower offset portion 40 may be formed with a socket and the upper portion 41 formed with a detent 42 adapted to snap into said 50 socket to hold the ends 40 and 41 against accidental separation.

Since the split is at one end of the loop, when the loop is spread or opened, the two sides of the 55 loop open like jaws bending about the other end of the loop thus facilitating the opening or spreading operation.

Although the loop has been illustrated in the drawing as being of hour glass shape, it will be understood that my invention may be embodied 60 in key retaining loops of other shapes, for example, oval or any other elongated loop shape. Furthermore, although my improved loop has been illustrated in the drawing as applied to a 65 key holder having pivoted strap members mounted on pivoted caps, as illustrated in my Patent No. 1,634,115 issued June 28, 1927, it will be understood that the invention may be embodied in key holders of various types and mounted either 70 on pivoted straps or on fixed straps, or any other loop supports.

It will thus be seen that there is provided a 75 device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing 5 is to be interpreted as illustrative and not in a limiting sense.

Having thus described my invention, I claim as new my desire to secure by Letters Patent:

1. In a key holder, in combination, a plate supporting a pin, a plurality of members individually pivoted about the axis of said pin and each having a strap portion, and a key retaining loop receiving each strap portion, each loop being made of an elongated flat strip of metal bent to form 15 a continuous split loop, said loop having at the split thereof, tabs disposed side by side with the end edges of the strip in engagement.

2. A key retaining loop for a key holder made of a single elongated flat strip of resilient metal, 20 said loop being generally of hour glass shape and having a relatively large loop portion at one end and a relatively small loop portion at the other end with a constricted intermediate portion, the small loop portion being split to form symmetrical 25 tabs disposed side by side in edge-contacting relation.

3. In a key holder, in combination, a plate supporting a pin, a plurality of members individually pivoted about the axis of said pin, a strap 30 on each of said members rotatable about an axis perpendicular to the axis of said pin, a loop receiving each of said strap portions, said loop being split, with the end edges of said loop in edge-contacting position, whereby said loops may 35 be spread open and individually removed from said straps.

4. A key retaining loop for a key holder made of a single, elongated, flat strip of resilient metal, 40 said loop being of hour glass shape having a larger loop portion, a smaller loop portion, and an intermediate constricted portion, the top of 45 said smaller loop portion being split to permit the loop to be spread open for separating said split ends to permit insertion of a key between 50 said split ends for engagement with said loop or removal of a key from said loop.

5. A key retaining loop for a key holder made of a single, elongated, flat strip of resilient metal, 55 said loop being of hour glass shape having a larger loop portion, a smaller loop portion, and an intermediate constricted portion, the top of 60 said smaller loop portion being split to permit the loop to be spread open for separating said split ends to permit insertion of a key between 65 said split ends for engagement with said loop or removal of a key from said loop, each split end having a shoulder engaging the other split end serving as a stop to limit movement of said split ends toward one another.

6. A key retaining loop for a key holder made of a single, elongated, flat strip of resilient metal, 70 said loop being of hour glass shape having a larger loop portion, a smaller loop portion, and an intermediate constricted portion, the top of 75 said smaller loop portion being split to permit the loop to be spread open for separating said split ends to permit insertion of a key between said split ends for engagement with said loop or removal of a key from said loop, said smaller loop, at said split, having similar symmetrically disposed tabs in side by side, edge contacting relation.

7. A key retaining loop for a key holder made of a single, elongated, flat strip of resilient metal, 75

- said loop being of hour glass shape having a larger loop portion, a smaller loop portion, and an intermediate constricted portion, the top of said smaller loop portion being split to permit 5 the loop to be spread open for separating said split ends to permit insertion of a key between said split ends for engagement with said loop or removal of a key from said loop, the adjacent split ends overlapping, and at least one being offset to form a shoulder engaging the end edge of the other.
8. A key retaining loop for a key holder made of a single, elongated, flat strip of resilient metal, said loop being of hour glass shape having a larger loop portion, a smaller loop portion, and an intermediate constricted portion, the top of 15 said smaller loop portion being split to permit the loop to be spread open for separating said split ends to permit insertion of a key between 20 said split ends for engagement with said loop or removal of a key from said loop, the adjacent split ends overlapping, and at least one being offset to form a shoulder engaging the end edge of the other, said overlapping portions having a pin 25 and socket snap connection.
9. A key retaining loop for a key holder made of a single, elongated, flat strip of resilient metal, said loop being of hour glass shape having a larger loop portion, a smaller loop portion, and 30 an intermediate constricted portion, the top of said smaller loop portion being split to permit the loop to be spread open for separating said split ends to permit insertion of a key between 35 said split ends for engagement with said loop or removal of a key from said loop, said smaller 40 loop, at said split, having similar symmetrically disposed tabs in side by side, edge contacting relation, and said tabs being disposed substantially at right angles to the longitudinal axis of said key holder, and remaining in edge to edge contact throughout progressively decreasing lengths as said holder is spread open.
10. A key retaining loop for a key holder made of a single, elongated, flat strip of resilient metal, said loop being of hour glass shape having a larger loop portion, a smaller loop portion, and an intermediate constricted portion, the top of 45 said smaller loop portion being split to permit the loop to be spread open for separating said split ends to permit insertion of a key between said split ends for engagement with said loop or removal of a key from said loop, said smaller loop, at said split, having similar symmetrically disposed tabs in side by side, edge contacting relation, said tabs being disposed substantially at right angles to the longitudinal axis of said key holder, and remaining in edge to edge contact throughout progressively decreasing lengths as 50 said holder is spread open, the end of each tab abutting a shoulder at the inner end of the other tab to serve as stops to limit movement of said split ends of said holder toward each other.
11. In a key holder, in combination, a key retaining loop made of a single, elongated resilient piece of metal, said loop being generally of hour glass shape having an intermediate constricted portion, and loop portions on either side of said constricted portion, one of said loop portions being smaller than the other, and said smaller loop portion being split, a support extending through the smaller loop portion, the smaller of said loop portions, and the larger loop portion being adapted to receive a key being split.
12. In a key holder, in combination, a key retaining loop made of a single, elongated resilient piece of metal, said loop being generally of hour glass shape having an intermediate constricted portion, and loop portions on either side of said constricted portion, one of said loop portions being smaller than the other, and said smaller loop portion being split, a support extending through the smaller loop portion, and the larger loop portion being adapted to receive a key, the smaller of said loop portions being split, and said smaller loop, at said split having similar symmetrically disposed tabs in side by side, edge contacting relation.
13. In a key holder, in combination, a key retaining loop made of a single, elongated resilient piece of metal, said loop being generally of hour glass shape having an intermediate constricted portion, and loop portions on either side of said constricted portion, one of said loop portions being smaller than the other, and said smaller loop portion being split, a support extending through the smaller loop portion, and the larger loop portion being adapted to receive a key, the smaller of said loop portions being split, said smaller loop, at said split having similar symmetrically disposed tabs in side by side, edge contacting relation, said tabs being disposed substantially at right angles to the longitudinal axis of said loop.
14. In combination, a member, a plurality of loop supports thereon, a key retaining loop on each support, each loop being made of a single elongated strip of resilient metal and being of hour glass shape, and having an intermediate constricted portion and loop portions on each side of said constricted portion, one loop portion being smaller than the other loop portion, the smaller loop portion being split, said loop supports passing through the smaller loop portions, said larger loop portions being adapted to receive a key, said loops being removable individually from their respective supports by spreading said loops apart at their splits, and said keys being movable from the larger loop portions to the smaller loop portions upon spreading the loops open to enlarge the space at the constriction, and said keys being removable from said loops by the spreading of said loops apart, the removal of one loop from each support being independent of the other loops.

ISIDOR NEWMAN.
